United States Patent Office

Des. 211,224

Patented May 28, 1968

211,224

COMB

Jerome L. Asner, 2604 SW. 65th St., and Edward N. Campbell, 4068 61st St., both of Oklahoma City, Okla. 73159

Filed July 5, 1967, Ser. No. 7,711

Term of patent 14 years

(Cl. D86—8)

We claim:

The ornamental design for a comb, substantially as shown.
